(57) **CLAIM**

(21) Appl. No.: **29/272,351**

The ornamental design for a charging cradle for hands free ear set of portable phone, as shown and described.

(22) Filed: **Feb. 7, 2007**

DESCRIPTION

(30) **Foreign Application Priority Data**

Sep. 29, 2006 (KR) 30-2006-0040070

FIG. 1 is a perspective view of a charging cradle for hands free ear set of portable phone;

(51) **LOC (8) Cl.** **14-01**

FIG. 2 is a front view of the charging cradle for hands free ear set of portable phone of FIG. 1;

(52) **U.S. Cl.** **D14/223; D14/217**

FIG. 3 is a rear view of the charging cradle for hands free ear set of portable phone of FIG. 1;

(58) **Field of Classification Search** D14/137–138,

D14/140, 142, 148–149, 205, 206, 223, 224,

D14/217, 221, 229, 240, 251, 252, 253, 155,

D14/214; D13/107–108, 110; 379/454,
379/455, 446; 381/183, 187, 188, 430; 320/110,

320/111, 113, 115; 455/130, 344, 573

See application file for complete search history.

FIG. 4 is a left-side view of the charging cradle for hands free ear set of portable phone of FIG. 1;

(56) **References Cited**

FIG. 5 is a right-side view of the charging cradle for hands free ear set of portable phone of FIG. 1;

U.S. PATENT DOCUMENTS

FIG. 6 is a top plan view of the charging cradle for hands free ear set of portable phone of FIG. 1; and,

6,891,351 B2 * 5/2005 Chen 320/115
D512,050 S * 11/2005 Verding D14/240

FIG. 7 is a bottom plan view of the charging cradle for hands free ear set of portable phone of FIG. 1.
